Atty.

UNITED STATES PATENT OFFICE

FRANK L. GRANT, OF CHICAGO ILLINOIS

MILK BOTTLE LOCKING DEVICE

Application filed February 2, 1931. Serial No. 512,885.

This invention relates to a lock for the prevention of theft of milk bottles after they have been delivered to the consumer and left on his door step.

5 One of the objects of this invention is to provide a keyless lock for milk bottles which is simple in operation.

Another object is to provide a lock which is self adjustable to different diameters of milk bottle necks.

10 A further object is to provide a lock which requires no manipulation by the consumer.

A further object is to provide a lock of this nature which at the same time provides 15 a complete enclosure for the top of the milk bottle whereby the top of the bottle remains clean and sanitary, and prevents other disturbance of the bottle top and its contents.

Another object is to provide a lock secured 20 to the outer frame of a door, and abutting against the door, whereby after a bottle has been delivered and locked by this device, the lock cannot be again opened from the outer side so long as the bottle remains within it, 25 and yet the bottle may be withdrawn with ease from the lock when the door is opened.

In the drawings is shown the preferred 20 embodiment of my invention, in which,

Figure 1 is a vertical sectional view.
30 Figure 2 is a plan view of the lock from the side abutting the door.

Figure 3 is a view of the lock mounted in its operative position with the milk bottle locked in it.

35 Referring to the drawings 10 indicates a door frame on which the lock is mounted so that the open side of the lock abuts against the door when the door is closed, and forms a part of the locking system. The end 11 is secured to the frame either by screws as 40 shown in the drawings, or it may be secured by a removable fastening device so that the entire lock may be removed when desired.

The top 12, side 13, and flange 14 are preferably formed of one piece as shown in the 45 drawings and welded to the end 11, although the individual parts may be made and secured together in any other conventional manner. A second flange 15 is secured to, or 50 forms a part of the locking end 16.

Secured to the inner side of side 13 is a housing 17 which carries the lock bolt 18. This lock bolt is secured to the end 16, and has a number of ratch-like teeth in it. A locking pin 19 is preferably secured to the side 13 and projects into an opening in the housing 17 to engage the lock bolt teeth. The construction of this pin is such that when it is raised to the extent of striking the top 12 it will not be withdrawn from the bolt housing, although it will 55 disengage the teeth. It is also preferably constructed of a flat or angular strip and fits into a like opening in the bolt housing to prevent the pin from turning out of position. The head of the pin is preferably a continuation of the same piece turned at a right angle and lies flat against the side wall. The purpose of this being that it cannot be disengaged from the lock bolt by any movement 60 of the bottle held within the lock, or by the insertion of any fine instrument into the lock through its bottom.

At one end the lock bolt has a turned up end or stud 20 which protrudes through a slot in the lock bolt housing which limits 75 the withdrawal of the bolt. A spring 21 is carried in the housing adjacent the end 11 and acts on the lock bolt urging it outwardly when the locking pin is manually raised out of engagement with the teeth.

80 In operating the device, when the door is closed the milkman inserts his finger into the lock from beneath and raises the locking pin. This releases the slide 16 which springs outwardly. The top of the bottle is then inserted upwardly into the lock through the open bottom, and the side 16 pushed in as far as it will go, the flanges 14 and 15 gripping the neck of the bottle between them below the flange of the bottle. The pin drops into the teeth and holds the side locked, and the device cannot be opened from the outer side of the door, the locking pin being inaccessible in this position.

85 Although milk bottles are generally of the same width at their lower portions, many of them vary in size at the neck. This device overcomes this variation by having its locking position adjustable by means of the series of locking teeth, and allows bottles of 90 100

varying neck size to be equally well locked.

To withdraw the bottle it is necessary to open the door from which side it is merely withdrawn without the necessity of manipulating the lock, and no resetting of the lock is required.

It is obvious that the lock may be mounted on any part of the door frame or against a window.

10 What I claim is:

1. In an article of the class described, a body comprising a stationary top, side, end and a movable end, secured to the frame of a door in abutting relation to the door which forms the other side; flanges carried by said ends to engage the neck of a bottle below the bottle flange, and adjustable locking means carried by said body enclosure whereby bottles of various neck diameters may be locked therein after being inserted into the enclosure, said locking means comprising a bolt secured to said movable end sliding in a housing carried by said stationary side and means for holding said bolt in different locking positions to form an end closure, the bottle being removable when the door is opened.

2. In an article of the class described, a body comprising a stationary top, side, end and a movable end, secured to the frame of a door in abutting relation to the door which forms the other side; flanges carried by said ends to engage the neck of a bottle below the bottle flange, and adjustable locking means carried by said body enclosure whereby bottles of various neck diameters may be locked therein after being inserted into the enclosure, said locking means comprising a bolt secured to said moveable end and sliding in a housing carried by said stationary side, said bolt having a series of teeth designed to be engaged by a locking pin extending through said housing into locking engagement with said teeth, whereby said bolt may hold said end locked to form an enclosure of varying size over the top of the bottle.

3. In an article of the class described, a body comprising a stationary top, side, end and a movable end, secured to the frame of a door in abutting relation to the door which forms the other side; flanges carried by said ends to engage the neck of a bottle below the bottle flange, and adjustable locking means carried by said body enclosure whereby bottles of various neck diameters may be locked therein after being inserted into the enclosure, said locking means comprising a bolt secured to said movable end and sliding in a housing carried by said stationary side, said bolt having a series of teeth designed to be engaged by a vertically disposed locking pin adjacent said side, and extending through said housing into locking engagement with said teeth, the teeth being

designed to allow inward movement of said end, but against outward movement, whereby the bolt may hold the end locked to form a variable enclosure, and means for opening said lock after the bottle has been withdrawn comprising a spring carried in the bolt housing which urges the adjustable end outwardly when said locking pin is manually raised out of engagement with the bolt teeth.

In witness whereof I affix my signature. 75
FRANK L. GRANT.
